UNITED STATES PATENT OFFICE

110,809

DESIGN FOR A TEXTILE FABRIC

Corinne C. Half, Pittsburgh, Pa.

Application January 13, 1938, Serial No. 74,272

Term of patent 3½ years

To all whom it may concern:

Be it known that I, Corinne C. Half, a citizen of the United States and residing at Pittsburgh, in the county of Allegheny and State of Pennsylvania, U. S. A., have invented a new, original, and ornamental Design for a Textile Fabric, of which the following is a specification, reference being had to the accompanying drawing, forming a part thereof, wherein the figure is a plan view of a piece of textile fabric showing my new design.

I claim:

The ornamental design for a textile fabric, substantially as shown.

CORINNE C. HALF.
